Filed Dec. 23, 1974, Ser. No. 535,721

Term of patent 7 years

Int. Cl. D10—06

U.S. Cl. D10—111

FIG. 1 is a front perspective view of a wide angled reflector unit showing our design.

FIG. 2 is a front elevational view thereof.

FIG. 3 is a top plan view thereof.

FIG. 4 is a rear elevational view.

FIG. 5 is a bottom plan view thereof.

FIG. 6 is an edge view taken on line 6—6 of FIG. 1.

FIG. 7 is a side elevational view thereof.

FIG. 8 is a sectional view taken on line 8—8 of FIG. 4.

The faceting is partially shown for convenience of illustration, it being understood that the faceting is continuous over the area indicated.

We claim:

The ornamental design for a wide angled reflector unit, as shown and described.
